LEVER CLAMP JACK

Filed Sept. 26, 1929

Inventor:
Fred E. Muzzey.
by Lester L. Sargent
Atty.

UNITED STATES PATENT OFFICE

FRED E. MUZZEY, OF HAVERHILL, MASSACHUSETTS

LEVER-CLAMP JACK

Application filed September 26, 1929. Serial No. 395,320.

The object of my invention is to provide an improved and more efficient lever clamp jack for use in the wood heel industry; and especially for holding the block while it swings against cutters to be shaped into a heel; and to provide a device of this character which is readily adjustable; and to provide a novel combination and arrangement of parts in such a device.

I attain these and other objects of my invention by the device illustrated in the accompanying drawings, in which—

Figure 1 is a side elevation of my invention partly in section to show the spring 43 in detail.

Fig. 2 is a rear elevation of a portion of the invention with member 18 raised to a vertical position.

Referring to the accompanying drawings, I provide a conventional spindle 1 provided with suitable collars (not shown) for convenience in mounting, and supporting the plates 2 and 5. Plate 5 is provided with a jaw portion 4 to engage the top portion of the inverted wood heel blank or block W. Rigidly secured to plate 5 is an upright 31 which is slotted to engage over the plate and which is bolted to it by the bolts 36 and held firmly in place by the pins 35 and 34, the latter engaging the notched edges 32 of the upright. I provide either a slot 38 as indicated in the drawings or a series of openings, the mechanical equivalent of the slot, to permit of adjusting the position of the upright relative to plate 5 by means of bolts 36.

Among the novel elements of my invention is the handle 7, the shank 6 of which is pivotally mounted on plate 5 by bolt 9; and the turnbuckle 11, the end 10 of which is pivotally connected by bolt 8 to shank 6 of handle 7 while its other end 12 is pivotally connected by bolt 15 to the knuckle joint links 14, and 14'. The lower ends of links 14' are pivotally connected by bolt 17 to the upright 31 and the upper links 14 are pivotally connected by bolt 16 to the knuckle joint lever 18 which is pivotally mounted by bolt 19 on the extension 20 of upright 31.

I provide a clamping screw 24 with the

usual hand wheel 25, the clamping screw being mounted in the head 22 of knuckle joint lever 18. I provide as one of the novel elements of the device a spring 28 interposed between the hand wheel 25 and the head 22 of knuckle joint lever 18. The lower end of the clamping screw 24 engages a novel round sleeve nut 27 which has a key way cut in its to prevent it from turning. It slides up and down through part 31.

I provide a heavy spring 43 interposed between the round sleeve nut 27 and the end 22 of knuckle joint lever 18. I also provide washers 44 above spring 43 and below spring 28 adjacent to end 22 of lever 18. Upper clamp member 29 is provided with a jaw 40 which engages the wood heel blank W as illustrated. I provide a flat plate spring 39 affixed to upper clamp member 29 and extending into the slotted portion of upright 31 and engaging that element to exert resilient pressure on the clamp member 29.

The provision of the handle, turnbuckle, knuckle joint mechanism, and lever, and springs 43 and 28 and sleeve nut are all improvements over the prior art and permit of efficient and rapid operation of the jack.

The operation of the device will be obvious from the foregoing description in connection with the accompanying drawing, in which the device is illustrated in operative position engaging the wood heel blank. To release this wood heel blank the handle member 7 is raised.

The heavy spring 43 is to take care of variations of thicknesses of blocks W and also is strong enough to hold spring tension on part 29 that clamps onto block W while it is being turned. The purpose of the steel ball 41 on the end of clamping screw 24 is to make the device operate easier, by reducing friction at the point of contact of ball 41 and part 29. There are two toggle links 14 and two toggle links 14'—four in all, two on each side. When pin or bolt 15 is thrown past center by adjusting nut 11 and screw threaded members 12 and 10 and handle 7, it will act as a lock. The round sleeve nut 27 slides up and down through the channel portion of part 31 being

held from turning by a suitable key set in 31 (not shown). Spring 28 which is a light spring is used to lift shaft 24, handle 25, nut 27, and the heavy spring 43 when the jack is 5 open. Parts 21 and 31 are riveted together in effect being equivalent to an integral piece, while part 20 is integral with 31, there being a pair of the members 31 each having the ear 20. I provide a suitable turnbuckle check 10 nut 18, as shown in Fig. 1.

To raise part 31 up or down the clamping screws 36 and 37 on part 5 are used to adjust the jack for different heights of heels, and turnbuckle 11 is also used for the same purpose and locks the jack at the same time.

It is necessary to have a collar on part 1 to go between what is called a crane on a turning machine. Part 5 rides on the track (not shown) so that it will not lift. The jack is 20 used to hold the rough block W while it swings against cutters to be properly shaped into a wood heel.

I provide a ball end 41 on the lower end of the clamping screw 24 to engage the upper 25 surface of upper clamp member 29 which is pivotally secured by a suitable bolt or pivot 30 to the upright 31. The ball end makes the device work more easily by reducing friction.

I may utilize a suitable or conventional gage 30 42 adjustably bolted to member 5 and having its end engaging the breast of a wood heel W or the corresponding portion of the block blank to set the block in the proper position between the clamping plates 4 and 40.

35 I may utilize a suitable or conventional wooden form or leader 26 the peripheral portion "Y" being used for shaping the heel as it rides against a part of the wood heel turning machine.

40 What I claim is:

1. In a lever clamp jack having means for supporting a wood heel blank including a spindle, jaw, and plate members, the combination with such members of a handle, the 45 shank of which is pivotally mounted to the aforesaid plate, an upright rigidly affixed to the plate and having a clamping screw journaled in its upper end, a hand wheel to adjust the clamping screw, a slidable sleeve, 50 nut on the lower end of the clamping screw, a knuckle joint lever pivotally mounted on the upper end of the upright and engaging the clamping screw, a spring interposed between the hand wheel of the clamping screw 55 and the end of the knuckle joint lever, a second heavy spring interposed between the knuckle joint lever and the aforesaid sleeve nut, links operatively connecting the other end of the knuckle joint lever with the upright, and a turnbuckle operatively connecting said link with the handle member.

2. In a lever clamp jack having means for supporting a wood heel blank including a spindle, jaw, and plate members, the combination with such members of a handle, the 65

shank of which is pivotally mounted to the aforesaid plate, an upright rigidly affixed to the plate and having a clamping screw mounted in its upper end, a hand wheel to adjust the clamping screw, a sleeve nut on the lower end of the clamping screw, a knuckle joint lever pivotally mounted on the upper end of the upright and engaging the clamping screw, a spring interposed between the hand wheel of the clamping screw and the end of the knuckle joint lever, a spring 70 interposed between the knuckle joint lever and the sleeve nut, links operatively connecting the other end of the knuckle joint lever with the upright, a turnbuckle operatively connecting said links with the hand lever, a pivotally mounted upper clamping jaw to engage the wood heel blank, a flat spring engaging the upright and affixed to the said upper clamp member to tend to lift same upwardly.

3. In a lever clamp jack of the type described, the combination of supporting means including means for engaging one end of a wood heel blank, an upright slotted to adjustably engage over said supporting means, a handle pivotally mounted on the supporting means, a turnbuckle pivotally connected to the shank of the handle, links to which the turnbuckle is pivotally connected, a knuckle 80 joint lever pivotally mounted on extensions of the upright, said links being pivotally connected to the upright and to said knuckle joint lever, a clamping screw having a hand wheel, said clamping screw being engaged by said knuckle joint lever, a sleeve nut on the lower end of the clamping screw, a spring interposed between the hand wheel of the clamping screw and the end of the knuckle joint lever, a second spring interposed between the knuckle joint lever and the sleeve 85 nut, an upper clamp member in operative engagement with the lower end of the clamping screw and adapted to engage the wood heel blank, and a flat spring engaging said upper clamp member to tend to lift same upwardly.

4. In a lever clamp jack having means for supporting a wood heel blank including a spindle, jaw and plate members, the combination with such members of a handle the shank of which is pivotally mounted to the aforesaid plate, an upright rigidly affixed to the plate and having a clamping screw carrying a hand wheel on its upper end journaled in its upper end, a sleeve nut on the lower end of the clamping screw, a knuckle joint lever pivotally mounted on the upper end of the upright and engaging the clamping screw, a spring interposed between the hand wheel of the clamping screw and the end of the knuckle joint lever, a spring interposed between the knuckle joint lever and the sleeve nut, links operatively connecting the other end of the knuckle joint lever with 120 125 130

the upright, a turnbuckle operatively connecting said link with the handle lever, a pivotally mounted upper clamping jaw to engage the wood heel blank, the aforesaid 5 clamping screw having a ball end to engage the upper clamping jaw, and a flat spring engaging the upright and affixed to the said upper clamp member to tend to lift same upwardly, the end of the clamping screw engaging the top of the upper clamp member.
